[57] CLAIM

The ornamental design for the earring center, as shown and described.

DESCRIPTION

FIG. 1 is a front elevational view of the earring center showing my new design, the various parts have been separated for ease of illustration;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof;

FIG. 7 is a front elevational view of an alternative embodiment of the earring center;

FIG. 8 is a rear elevational view thereof;

FIG. 9 is a left side elevational view thereof;

FIG. 10 is a right side elevational view thereof;

FIG. 11 is a top plan view thereof; and,

FIG. 12 is a bottom plan view thereof.

The broken line showing of earrings in FIG. 1 is for illustrative purposes only and forms no part of the claimed design.
